G. A. PETTIT

LUBRICANT GUN

Filed April 22, 1922

UNITED STATES PATENT OFFICE.

GEORGE A. PETTIT, OF NEW ORLEANS, LOUISIANA.

LUBRICANT GUN.

Application filed April 22, 1923. Serial No. 585,937.

To all whom it may concern:

Be it known that I, GEORGE A. PETTIT, a citizen of the United States, and resident of New Orleans, in the parish of Orleans and State of Louisiana, have invented certain new and useful Improvements in Lubricant Guns, of which the following is a specification.

My invention relates to devices for forcing a lubricant into suitable receptacles or cups, and it consists in the combinations, constructions and arrangements herein described and claimed.

An object of my invention is to provide a device of the character described which is designed primarily for use in filling the rod cups on locomotive engines.

A further object of my invention is to provide a device of the character described which is of simplified construction and embodies means adapted to be quickly and easily applied to all rod cups of locomotive engines and which is adapted to be operated conveniently to force a relatively hard lubricant therefrom into the oil cups.

A still further object of my invention is to provide a device of the character described which is not likely to get out of order easily in service, and which is thoroughly practical commercially.

Other objects and advantages will be apparent from the following description, the novel features of the invention will be particularly outlined in the appended claims.

My invention is illustrated in the accompanying drawings, forming a part of this application, in which—

Figure 1 is a view mainly in side elevation and partly in vertical section, showing a practical embodiment of the invention operatively applied to an oil cup, a fragmentary portion of which is shown,

Figure 2 is a group view, showing in perspective two of the elements comprised in the embodiment of the invention exhibited in Figure 1 and a fragmentary portion of another element of the same embodiment, the elements being shown separated from one another.

In carrying out my invention, I provide a barrel 1 which is reduced diametrically at 2 at an appreciable distance from its lower end and is reduced still further at 3 at a short distance from its lower end and screw threaded externally, as indicated at 4,

or internally to provide a nozzle portion which is adapted for connection with an internally (or externally) threaded filler neck 5 of an oil cup or like receptacle, as will be understood from the following.

The barrel 1 is open at its upper end and the bore thereof, which is designated at 6, is diametrically reduced, at a short distance from the lower end thereof to provide an annular shoulder 7 and a restricted discharge orifice or passage 8 leading through the nozzle portion 3 of the barrel.

An outwardly extending integral flange 9 is formed on the body of the barrel intermediate of its length and at a desirable distance above the upper end of the portion 2. A collar 10 which is slipped over the lower end of the barrel or the nozzle portion thereof and which is adapted to rotate upon the portion of the barrel below the flange 9 is held against downward movement along the barrel by means of a jam nut 11 which is adapted to engage the threads 12 of the relatively reduced portion 2 and to support the collar 10 with the upper end thereof adjacent to the flange 9.

The collar 10 has a pair of horizontally spaced vertical ears or lugs, 13, 14 extending laterally thereof. The connecting rod or link 15 has its lower end disposed between the lugs 13, 14 and is pivotally attached to the latter, as by means of a pin 16. The connecting rod 15 is pivotally attached, at its upper, as by means of a pin 17 to one end of a lever 18 which is pivotally attached intermediate, as at 18 to a cap 19 which is connected with a plunger 19 at the upper end of the latter in a manner which will now be described.

The plunger 19 is of a size diametrically to reciprocate in the relatively large bore of the barrel and to rest at its lower end upon the shoulder 7 when moved to the limit of its downward stroke. The plunger 19 has a substantially integral, flat head 20 which is held in axial alignment with an integral shank portion 21 depending from the cap by means of a union nut or coupling 22 having a bore 23 adapted to loosely receive the plunger 19 and a counter bore 24 at the upper end thereof adapted to receive the head 20 and being threaded for engagement with the shank 21 of the cap, the said shank being cooperatively threaded. The arrangement is such that the plunger 19

is held against axial movement relatively to the cap 18 but can rotate independently thereof.

The barrel 1 is provided with a lateral opening 25 which is formed through the walls of the body thereof above the flange 9.

From the foregoing description of the various parts of the device, the operation thereof may be readily understood. Since the barrel 1 and the plunger 19 are mounted to rotate independently of the connected together collar 10 and the cap 18, it will be apparent that the body 1 can turn to engage the nozzle portion 3 of the barrel with threaded filler openings of lubricant receptacles without there being any necessity of moving the lever 16, which might be impracticable in instances on account of the space required therefor. The body of the barrel 1 is preferably provided with an enlargement 26 at its upper end which is formed with a plurality of faces 27 which are adapted to be gripped by a wrench or like tool to effect the adjustment of the barrel with respect to an oil cup or receptacle, if required.

When the barrel 1 has been applied to a receptacle in the manner described, the lever 16 is swung upward until the lower end of the plunger 19 is positioned above the lateral opening 25 through the body of the barrel. A quantity of a relatively hard lubricant, which in the service for which used in connection with the lubrication of crank pins and like moving parts of a locomotive engine is a grease having the consistency of hard yellow laundry soap, is introduced through the opening 25 into the barrel until the bore or chamber thereof is filled to the level of the opening 25. A pressure is then applied to the lever 16 and the plunger 19 is moved downward, thereby forcing the relatively hard lubricant through the reduced passage 8 into the oil cup or receptacle. The dotted lines in Figure 1 indicate the position from which the plunger 19 will be moved relatively to the barrel 1 to effect the forcing of a lubricant disposed in the barrel through the nozzle 3 into the receptacle with which the nozzle is connected at its lower end.

The device is simple in construction and can be readily applied and operated.

Obviously my invention is susceptible of embodiment in forms other than that illustrated in the accompanying drawings and I

therefore consider as my own all modifications of the forms of the device herein disclosed, which fall within the scope of the appended claims.

Having thus described my invention, what I claim is:—

1. A lubricant gun comprising a barrel having a nozzle at one end adapted for connection with a lubricant receptacle and having a lateral opening formed through its walls at an appreciable distance from the inner end of the nozzle portion the bore of said barrel being reduced diametrically to define an annular shoulder at the inner end of the nozzle portion and to provide a reduced passage through the nozzle portion, a plunger movable in the barrel from the end thereof remote from the nozzle portion past the lateral opening into abutting relation at its end with the said shoulder, a collar rotatably mounted upon the barrel adjacent to the nozzle portion thereof, a cap rotatably mounted upon the plunger at the end thereof remote from the nozzle portion of the barrel, and a lever and link arrangement connecting the collar and the cap for reciprocating the plunger in the barrel.

2. A lubricant gun comprising a barrel having a nozzle at one end adapted for connection with a lubricant receptacle and having a lateral opening formed through its walls at an appreciable distance from the inner end of the nozzle portion, the bore of said barrel being reduced diametrically to define an annular shoulder at the inner end of the nozzle portion and to provide a reduced passage through the nozzle portion, a plunger movable in the barrel from the end thereof remote from the nozzle portion past the lateral opening into abutting relation at its end with the said shoulder, a collar rotatably mounted upon the barrel adjacent to the nozzle portion thereof, said collar having a pair of spaced substantially radial lugs outstanding therefrom, a cap rotatably mounted upon the upper end of the plunger and being held against axial movement relatively to the latter, a lever pivotally attached intermediately to the upper end of the cap, and a connecting rod pivotally attached at one end to one end of the lever and pivotally supported at its other end between the outstanding lugs on the collar.

GEORGE A. PETTIT.
